UNITED STATES PATENT OFFICE.

OSCAR N. RITCHIE, OF HAMILTON, AND HERBERT C. BOYKIN, OF MIDDLETOWN, OHIO, ASSIGNORS TO P. LORILLARD COMPANY, OF NEW YORK, N. Y., A CORPORATION OF NEW JERSEY.

BAG-OPENING MACHINE.

Application filed June 10, 1922. Serial No. 567,316.

To all whom it may concern:

Be it known that we, OSCAR N. RITCHIE and HERBERT C. BOYKIN, both citizens of the United States and residents of Hamilton and Middletown, respectively, in the county of Butler and State of Ohio, have invented certain new and useful Improvements in Bag-Opening Machines, of which the following is a specification.

10 This invention relates to a bag opening machine, and more particularly to a machine for receiving, opening and delivering bags in succession to a bag filling mechanism, and has special reference to the provision 15 of an improved bag opening machine of the type disclosed in the patent to Henderson and Tietz, No. 1,111,899, of September 29, 1914.

In bag opening machines of this type a 20 carrier in the form of a turntable provided with a plurality of spaced bag holders is rotated with each of the holders moved through bag receiving, opening, and delivering stations, for receiving bags from a 25 feeding means, for opening the same to be filled with a commodity such as tobacco, and for delivering the same in opened condition to a bag filling mechanism. The turntable is intermittently rotated with each holder 30 successively positioned at each of the said stations. When a holder with a bag therein is positioned at the bag opening station, a bag opening mechanism is moved into co-operative relation with the bag holder and 35 the bag therein, the said bag opening mechanism including a spoon element which is reciprocated towards and from the bag holder and which when moved towards the bag holder enters a bag therein and opens the 40 same. Where uniform bag opening results are desired to be attained, it has been found to be essential that the co-relation between a bag holder and the bag opening spoon be uniform in the operation of the machine, 45 and more particularly that the bag holders be positioned centrally with respect to the bag opening spoon each time they arrive at the bag opening station, and that the bag opening spoon be so operated as to move 50 into the bag with regularity, at the proper speed and without vibration, the certainty of opening each bag being largely dependent upon these factors. When the bag opening

spoon fails in properly entering a bag and opening the same, the bag when advanced 55 to the delivering station is not properly removed by a bag removing mechanism operating at the said delivering station, failure of removal of a bag from a holder resulting in the automatic stopping of the machine, this 60 to prevent the activity of the filling machine in the absence of a bag fed thereto. The prime desideratum of the present invention relates to the provision of an improved bag 65 opening machine in which the bag opening mechanism and its co-operation with the rotatable turntable are improved, so that the bags when successively positioned at the bag opening station will be opened with certainty, and so that the stopping of the machine 70 resulting from improper bag opening activity will be prevented.

The principal objects of the present invention may be said to include, besides the provision of an improved bag opening machine having the characteristics and capable 75 of performing the results above referred to, the further provision of a machine of this nature in which the bag opening mechanism is reciprocated in the machine framework 80 carrying the carrier or turntable, and in which the reciprocation of the bag opening mechanism is effected by a driving means journaled in the said framework; the further provision of a bag opening machine of 85 this nature combined with a bag feeding machine, with the parts so arranged that the bag opening mechanism is driven from the bag feeding machine in such manner that the opening spoon will be reciprocated with 90 regularity and without that vibration incident to prior machines of this type; the further provision of a bag opening machine of 95 this nature in which the turntable is intermittently operated with the holders successively positioned at the operating stations in definite and centered relation with respect to the mechanism at said operating stations; the still further provision of an improved bag opening mechanism operating to effect 100 the full opening of the bag so as to produce uniform results in the advancing of the same to the bag filling machine; and the provision of improved means for maintaining the bag in open condition after the same is operated 105 upon by the bag opening mechanism.

To the accomplishment of the foregoing and such other objects as may hereinafter appear, our invention consists in the elements and their relation one to the other, as hereinabove particularly described and sought to be defined in the claims, reference being had to the accompanying drawings which show a preferred embodiment of our invention and in which:

10 Fig. 1 is a side elevational view of the bag opening machine shown in conjunction with the bag feeding means,

15 Fig. 2 is a front elevational view thereof shown in conjunction with the bag removing mechanism,

20 Fig. 3 is a fragmentary cross-sectional view of the means for moving the carrier or turntable of the machine,

25 Fig. 4 is a front elevational view of the machine with parts shown in section and other parts broken away, and showing the parts at a stage of operation subsequent to the stage depicted in Fig. 2.

30 Fig. 5 is a fragmentary view of the bag feeding means.

35 Fig. 6 is a rear elevational view of a bag holder showing the means for operating the bag gripping devices, and

40 Fig. 7 is a plan view of the holder shown in Fig. 6.

45 Referring now in detail to the drawings, the bag opening machine A is associated with a bag feeding means generally designated as B, the bag opening machine operating for receiving bags individually fed from the bag feeding means, and being operative for opening the said bags and delivering the same to a bag removing means C, the latter receiving the bags individually for advancing the same to a filling mechanism (not shown) where the bags are filled with a commodity such as tobacco, and are subsequently sealed and packed.

50 The bag opening mechanism A comprises a rotatable carrier or turntable 10 rotatable about a central post 11 forming part of the stationary framework f of the machine, and a plurality of bag holders h', h², h³, and h⁴ arranged on the turntable 10 for movement therewith, each of the holders being movable to and past a plurality of operating stations including the bag receiving station s', the bag opening station s², an inactive station s³, and a bag delivering or removing station s⁴.

55 The bag holders are each rockably mounted on the turntable 10, each of the bag holders being movable from an inclined position, as shown at station s' or s², to a less inclined position, as shown at the bag removing station s⁴, and to this end each of the holders, such as h', is provided with a trunnion plate 12 journalled in opposed bearings such as 13 formed preferably integral with the turntable 10 (see particularly

Fig. 3), and for rocking each holder in the desired manner there is provided a stationarily mounted cam plate 14 fixed to the framework f of the machine, the cam plate being provided with a cam groove 15 (see 70 particularly Fig. 3) and cooperating with the cam groove each of the bag holders is provided with an arm 16 provided at one end with a cam follower 17 movable in the cam groove 15 and pivoted at its other end to spaced links 18, which in turn are pivoted to the trunnion plate 12 of the holder. Arranged above the cam plate 14 there is provided a locking plate 19 active for confining the levers 16 and for constraining 75 the cam followers 17 to movement within the cam groove 15. With the provision of this construction, it will be seen that upon rotation of the turntable 10 the plurality of holders spaced thereon will be moved to and past the operating stations, and in such movement the holders will be oscillated from a position shown at the station s² to a position shown at the station s⁴, the cam groove 15 being so contoured, as seen in Fig. 3, as 80 to effect this result.

85 The turntable 10 is given an intermittent motion, with the holders thereon successively stopped at the operating stations, and for the purpose of effecting the intermittent 90 rotation of the turntable, there is provided an oscillating lever 20 fulcrumed on the framework f of the machine, as at 21, the lower arm of the said lever being connected to a link 22, by means of the universal joint 23, the link in turn being connected by means of the universal joint 24 to an arm 25 95 oscillatably mounted in a reduced portion 26 of the post 11 and held on said post as by means of the washer 27 pinned to the post, said arm 25 being provided with a pawl 28, the said pawl being adapted to 100 successively cooperate with a plurality of depending studs 29 mounted on the said turntable 10. Each of the studs 29 comprises preferably a screw or bolt adjustably received by a suitably tapped bore 30 in the turntable 10 (see Fig. 4), the screw studs being locked in position on the turntable by 105 means of the lock nuts 31. The screw studs 29 are in effect tooth members cooperating with the pawl 28 as shown particularly in Fig. 3, a spring 32 anchored at one end to the arm 25 and at the other end to the pawl 28 being provided for normally urging the 110 pawl against a stop 33 on the said arm and in position to engage with a stud 29 for transmitting motion of the arm 25 to the turntable 10. The link 22 is preferably 115 made adjustable, and to this end comprises two rod portions connected together by an adjusting coupling 34. With the provision of this construction, it will be seen that as the lever 20 is oscillated, the actuating arm 25 will be oscillated to engage the spaced 120

studs or teeth 29 successively for effecting the intermittent rotation of the turntable 10 with the holders given alternate periods of rest and movement, and with the holders 5 positioned during the periods of rest at the respective operating stations.

The lever 20 is oscillated from a drive shaft 35 which receives motion from a prime mover connected to the drive shaft 10 through the chain and sprocket 36 and 37, the said drive shaft being provided with a gear 38 meshing with a gear 39 fixed to a shaft 40, and on the said shaft 40 there is provided an oppositely positioned gear 41 carrying eccentrically a link 42 which is pivotally connected to the upper arm of the lever 20. With the gear 41 rotating in the direction shown by the arrow in Fig. 1, it will be seen that the lever 20 is rocked 20 or oscillated to effect the desired rotation of the turntable.

When a bag holder such as h' is positioned at the bag receiving station s' , a bag is fed into the holder by means of the bag feeding mechanism B. Our bag feeding mechanism, which forms the subject-matter of our copending application 467,985, filed May 9, 1921, is shown in part in the figures, the said bag feeding mechanism comprising provisions for successively feeding bags individually from a bag magazine 43, where the bags are arranged in stacked relation, as shown at 44 in Figs. 1 and 2. The bag feeding means includes a plurality of gripper rollers 45 and 46 journaled in the framework f of the machine, the gripper rollers 45 being mounted in blocks 47 resiliently journaled in the side plates 48 of the machine, as by means of the springs 49. The gripper rollers 45 and 46 receive the bags such as b successively from the magazine 43, and advance these bags to superposed curling rollers 50 and 51 arranged in advance of the gripper rollers, the said curling rollers 50 and 51 being fixed to shafts 52 and 53 also journaled in the side plates 48, the curling rollers functioning to "iron out" the longitudinal central portion of a bag b in a manner shown in Fig. 2 of the drawings, the side portions of the bag being curled upwardly from the central longitudinal portion thereof, this so that the bags when received by the holder h' will lie with the central portion of the bag flat against the rear wall of the holder, this to facilitate the subsequent bag opening step. For directing and guiding a bag b to the holder h' as it is advanced by the curling rollers, there is provided the directing guide 54 arranged above a chute 55 upon which the bag falls as it moves from the rollers to the holder h' . For laterally guiding the bags in this movement, there are provided the side guards or plates 56.

The gripper and curling rollers are

driven from the drive shaft 40 of the machine, and to this end the shaft 57 of the lower gripper rollers 46 is provided at one end with a pinion 58 meshing with an idler 59, which in turn meshes with and is driven 70 by the gear 41, the other end of the shaft 57 being provided with a pinion 60 meshing with a pinion 61 fixed to the shaft 62 of the upper gripper rollers 45, the curling rollers being driven from the gripper rollers by means of idler 63 meshing with the pinion 60 and a pinion 64 upon the roller shaft 53, the other roller shaft 52 being also provided with a pinion 65 meshing with the pinion 64. The shaft 52 of the upper curling roller may also be resiliently mounted in the side plates 48 of the machine in a manner similar to the mounting of the upper gripper rollers, the journals of this shaft being to this end movably arranged in the 85 side plates and urged downwardly resiliently by means of the springs 66 (see Fig. 5).

For cooperating with the feeding means to effect individual feeding of bags, and to prevent multiple feeding of the bags, the magazine 43 of our invention is provided with aligning or bag adjusting means operative on the front edge of the stack of bags 44, the said bag adjusting means including the superposed cam elements 67 and 68 fixed to shafts 69 and 70 journaled in the opposed bearings 71 and 72, the said cam elements being driven in the direction shown by the arrows in Fig. 1 by means 90 of the gears 73 and 74, which in turn are driven from the bag feeding means, an idler 75 meshing with gear 73 and the driven pinion 61 being provided to this end, the idler 76 being provided for communicating motion of the gear 73 to the gear 74. The bag adjusting cam elements 67 and 68 in their rotation operate upon the front wall of the bag stack 44 for adjusting the bags in the stack to facilitate single bag selection, 100 as described and claimed in our copending application heretofore mentioned, Ser. No. 467,985.

After a bag holder such as h' receives a bag b from the bag feeding means, the turntable 10 is given a quarter turn so that the bag holder and bag assume the position at the bag opening station s^2 ready for the bag opening step. For opening a bag in the holder there is provided a reciprocable bag opening mechanism which moves towards the holder when the latter is positioned at the bag opening station, the said bag opening mechanism including a spoon which enters between the side walls of the bag and forces these walls apart to open the same. The bag opening mechanism preferably comprises a bag opening spoon 77 rotatably mounted on a cross bar 78 and rockable thereon about an axis 79, the spoon 77 being 115 120 125 130

to this end fixed to a spoon holder 80 provided with trunnions 81 rotatable in bearings 82 forming part of the cross bar 78. The spoon 77 is curved outwardly at its bottom end, as shown at 83, the said end being adapted to ride on the inside surface of a rear wall of the bag, as shown in Fig. 4, the body portion of the spoon 77 being concaved at its side edges to facilitate bag opening, the spoon being preferably provided also with a bulge spring 84 and being normally forced rearwardly by a spring 84'. To limit the rearward motion of the spoon as it is moved upwardly, the spoon holder 80 is provided with an adjustable set screw 85 locked by means of a lock nut 86, the shank of the said screw being adapted to abut against a stop 87 for limiting the rearward motion of the spoon. The cross bar 78 is guided for reciprocable motion in the framework f of the machine, and to this end the cross bar 78 is provided with integral spaced sleeve portions 88 slidable in the spaced guide rods 89 fixed to the stationary framework f of the machine. Upon movement of the cross bar 78 to and from a holder h^2 in the direction as shown by the arrows in Fig. 2, for example, the bag opening spoon enters a bag, opens the same and recedes therefrom to permit subsequent rotation of the turntable for advancing the bag for removal from the holder.

As heretofore mentioned, where uniform bag opening results are desired to be attained, it has been found to be essential that the co-relation between a bag holder and the bag opening spoon be uniform in the operation of the machine, and more particularly that the bag opening spoon be so operated as to move into the bag with regularity, at the proper speed and without that vibration incident to prior machines of this make, the certainty of opening each bag being largely dependent upon these factors. To the end of providing the desired certainty of bag opening, the bag opening spoon 77 is actuated by driving means journalled in the stationary framework f of the machine, and more specifically by means which is directly connected to the bag feeding means of the machine, all the operating parts for effecting spoon operation being thus mounted on the same framework in which the turntable is rotatable. To these ends we provide a drive shaft 90 journalled in upstanding bearings 91 fixed to the framework f of the machine, one end of the said shaft carrying a gear 92, and the other end of the said shaft being provided with a crank arm 93 connected to a link 94, which in turn is connected to the upstanding bearing portion 95 formed preferably integral with the cross bar 78. The shaft 90 is driven from the feeding means of the machine, and to this end the gear wheel 92 is arranged to mesh with the driven

gear 73 heretofore mentioned. The actuation or driving of the spoon 77 is suitably synchronized with the movement of the turntable 10, so that the opening spoon 77 is given a complete cycle of movement in the time that the turntable 10 is given a full quarter turn with a holder passing through a full period of movement and dwell. With the provision of this means, we have found that the desired speed of movement is imparted to the opening spoon 77, and that the same is moved with the regularity and smoothness essential for efficient service.

In addition to regulating the operation of the opening spoon 77, it is furthermore highly desirable, where uniform bag opening is desired as heretofore mentioned, that the bag holders be positioned centrally with respect to the bag opening spoon each time they arrive at the bag opening station; and to this end the invention includes the provision of means for stopping the turntable with the holders definitely located in a central position with respect to the opening spoon 77. For this purpose there are provided a plurality of balls 96 movable in the bores 30 in the turntable 10 and urged upwardly by means of springs 97 housed in the said bores, the balls cooperating with spaced sockets 98 spacedly arranged at 90° apart in the cam plate 14, the cooperation of these parts effecting the more definite positioning of the turntable 10 with the holders at the respective operating stations. For the purpose of taking up the wear of these parts, and for the more certain positioning of the holders in their desired locations, the invention further includes the provision of positive stop means comprising a stop rod 99 fixed to the hub 21 of the oscillating lever 20, the said stop rod 99 upon oscillation of the lever 20 being rockable into and out of the path of movement of the bag holders, the arrangement of parts and operation being such that the stop rod 99 is moved out of the said path of movement when a holder is to be advanced from one station to the next succeeding station and is moved into the said path of movement when a holder is approaching the bag opening station s^2 . As viewed in Figure 2 of the drawings and in dotted lines in Fig. 1, the bag holders have just completed the period of movement, the stop rod 99 co-acting with a side wall of the holder h^2 for stopping the same in the desired centralized position. It will be apparent viewing Fig. 1 that in the further rotation of the gear 41, the lever 20 is oscillated to bring the pawl 28 into contacting engagement with the next stud tooth 29, and that during this motion the stop rod 99 is moved upwardly out of the path of movement of the holder h^2 to permit subsequent operation of the turntable and rotation of the holders.

For effecting a full opening of a bag b , the

bag opening spoon 77, after it has partially entered a bag as shown in Fig. 4 of the drawings, is given a quick angular rotation about its axis 79, this for the purpose of imparting a final "kick" to the bag, so that the front and rear walls of the bag will assume the separated condition desired for a fully opened bag. To these ends, the spoon holder 80 is provided with a roller or cam follower 100 rotatable on a shaft 101 fixed to the spoon holder 80; and arranged in the path of movement of the said cam follower 100 there is provided a cam track 102 fixed to a plate 102' and mounted on the stationary framework *f* of the machine. As seen in Fig. 4, before the spoon 77 has fully entered the bag *b*, the cam follower 100 is engaged by and rides upon the cam track 102, the cooperation of these parts producing a quick angular movement in the spoon 77 and imparting the desired "kick" for fully opening the bag.

For maintaining the bag in opened condition after the same has been operated upon by the bag opening mechanism, there is provided a gripping means active for gripping the side edges of a bag *b* after the same has been opened. To these ends each of the bag holders is provided with bag gripping elements or fingers movable to and from the side edges of the bags for engaging the same during bag opening, and for releasing the same during bag removal. Each bag holder such as *h*' (see for example Figs. 6 and 7) is provided with the bell crank levers 103 and 104 rockably mounted on the rear wall 105 of the holder, as at 106 and 107 respectively, the upper arms of the said bell crank levers being provided with gripping elements or fingers 108 and 109 respectively, the said gripping fingers having suitable cut-out portions or notches 110 and 111 for receiving the side edges of a bag *b*, as shown in Fig. 7, when the gripping fingers are moved towards each other during opening of the bag. For moving the gripper fingers and the bell crank levers, there is provided a slide bar 112 provided at its bottom end with the spaced pins 113 and 114 received by the elongated notches 115 and 116 in the lower arms of the bell cranks 103 and 104, the upper end of the slide bar 112 being connected to an actuating shaft 117 by means of an arm 118 (see for example Fig. 4), fixed to the said shaft and pivotally connected to the slide bar 112, the said shaft 117 being journaled in a boss 119 forming part of the holder and being oscillatable by means of the reversely arranged actuating levers 120 and 121 pinned to the said shaft. It will be seen from this construction that as the shaft 117 is rocked in opposite directions, the gripper fingers 108 and 109 will be moved towards and away from each other to grip and release the bag *b*. For the pur-

pose of resiliently maintaining the gripper fingers in either their inward or outward positions, the slide bar 112 is provided with a spring pressed ball 122 which rides on the rear wall 105 of the holder to effect resistance to the movement of the gripper fingers, the said ball 122 being urged resiliently against the holder as by means of the spring 123 housed in a casing 124 forming part of the slide bar 112. For retaining a bag in the holder, the holder is provided with the bottom keepers 125 and with the side keepers 126.

For moving the gripper fingers 108 and 109, towards each other during bag opening, a reciprocable actuating rod 127 fixed to a bearing 128 forming part of the cross bar sleeve 88 is provided, the construction being such that the gripper actuating arm 120 is arranged in the path of movement of the rod 127 and is moved downwardly upon the descent of the rod and the engagement of the arm 120 by the said rod.

After a bag is opened and grippingly held in opened position, the turntable 10 is given another quarter revolution, so that the bag in the next succeeding holder is arranged to be opened and so that the bag in the next preceding holder is arranged at the bag removing station *s*⁴. The bag *b* is now ready to be removed from the bag holder such as *h*' and delivered to bag filling mechanism (not shown). For removing the bag the mechanism C is provided, the said mechanism including a bag entering member 129 mounted on a block 130 arranged for rotation and reciprocation relatively to the framework of the bag opening machine, the bag entering member 129 including a fixed member 131 and a relatively movable member 132, the latter member having the upwardly extending arm 133 carrying a roller 134 co-acting with a cam 135 mounted on the reciprocable but non-rotative head frame 136, the cooperation of these parts being such that the member 132 is shifted into proximity with the member 131 for bag entering travel in the descent of the latter. The members 131 and 132 enter the opened bag *b* at the station *s*⁴, and when the side edges of the bag are released the walls of the bag adhere to the bag entering members and move therewith in the upward or ascending travel of the latter. As the bag entering members travel into the bag, the gripping fingers 108 and 109 are moved to their outward positions, this being accomplished by the engagement of the actuating arm 121 by means of the reciprocable rod 137 mounted on a bar 138 fixed to the reciprocable and non-rotative head 136.

The operation of the machine will be fully apparent from the above detailed description thereof. It will be further apparent that during the dwell period of the turn-

table 10 a bag b is fed to a holder at the station s^1 , a bag is opened at the station s^2 , and a preceding bag is removed from the holder h^4 at the station s^4 for delivery to the bag filling machine. It will be further apparent that with the provision of our apparatus the bag holders are definitely stopped in centralized positions at the operating stations and especially at the bag 10 opening station, with the bag opening mechanism so operative that the spoon 77 enters with certainty between the sides of the bag and is moved with the regularity and speed desired for efficient service.

15 While we have shown our device in the preferred form, it will be obvious that many changes and modifications may be made in the structure disclosed without departing from the spirit of the invention, defined in 20 the following claims.

We claim:—

1. In combination with a bag removing means, of a bag opening machine comprising a carrier, provided with a bag holder, a framework in which the said carrier is journaled for movement through a plurality of operating stations including a bag opening station, a bag opening mechanism mounted independently of said bag removing 25 means and movable into and out of cooperative relation with the holder and a bag therein at such station, and provisions for operating said mechanism including a driving means journaled in the framework 30 which supports the said carrier.

2. In combination with a bag removing means of a bag opening machine comprising a turntable provided with a plurality of spaced bag holders, a supporting framework 40 including a central shaft on which the said turntable is rotatable, each holder being movable through a plurality of operating stations including a bag opening station, a bag opening mechanism mounted independently of said bag removing means and reciprocable into and out of cooperative relation with a holder and a bag therein at such station, and provisions for operating 45 said mechanism including a driving means journaled in the framework which supports the said turntable.

3. In combination with a bag removing means of a bag opening machine comprising a turntable provided with a plurality 55 of bag holders thereon, a supporting framework in which the turntable is rotatable, each holder being movable through a bag opening station, a bag opening mechanism mounted independently of said bag removing means and reciprocable towards and from the bag holder at such station for opening a bag in the holder, guide means in the said framework for guiding the reciprocation of the bag opening mechanism, 60 and provisions for operating the said mech-

anism including a driving means journaled in the framework which supports the said turntable.

4. In combination, a carrier provided with bag holders each movable through a bag receiving station, a bag opening station, and a bag delivery station, bag feeding means for feeding bags individually to the holders when at said bag receiving station, mechanism at the said bag opening station movable into and out of cooperative relation with a bag holder thereat for opening a bag in the holder, and provisions for operating the said mechanism including a driving means directly connected to said 80 bag feeding means.

5. In a bag opening machine, a carrier provided with a bag holder, a framework in which the said carrier is journaled for movement through a bag opening station, a bag opening mechanism mounted in said framework and movable into and out of cooperative relation with the holder and a bag therein at said station, and provisions for operating said mechanism including a 90 drive shaft and a crank arm directly connecting the said shaft with the said bag opening mechanism.

6. In a bag opening machine, a turntable provided with a plurality of bag holders spaced thereon and each movable through a bag opening station, a framework in which the said turntable is mounted, a bag opening spoon at such station mounted in said framework for reciprocation into and out of relation with a bag holder, and means for reciprocating the said spoon comprising a rotatable shaft, a link connected to the said spoon, and a crank arm connecting the said shaft and the said link.

7. In a bag opening machine, a turntable provided with a plurality of bag holders movable through a plurality of operating stations, means for intermittently moving the turntable with each holder successively positioned at the said stations, and provisions operative on the said turntable for stopping the same with the holders centered at the said stations, the said provisions comprising a stop rod movable into and out of the path of movement of a holder, and operative when moved into said path of movement for stopping the said holder in centered position.

8. In a bag opening machine, a turntable provided with a plurality of bag holders movable through a plurality of operating stations, means for intermittently moving the turntable with each holder successively positioned at the said stations, and provisions operative on the said turntable for stopping the same with the holders centered at the said stations, the said provisions comprising a stop rod movable into and out of the path of movement of a holder, and

operative when moved into said path of movement for stopping the said holder in centered position, the said stop rod being adjustable in length.

5 9. In a bag opening machine, a turntable provided with a plurality of spaced bag holders each movable through a plurality of operating stations, means for intermittently moving the turntable with the holders successively positioned in the said stations, the said means comprising an oscillating operating lever and elements connected to the said lever for intermittently engaging the said turntable, and provisions operative on the 10 said turntable for stopping the same with a holder centered at an operating station, the said provisions including a stop rod oscillatable with the said lever.

10. In a bag opening machine, a carrier provided with a bag holder movable through a plurality of operating stations including a bag opening station, a bag opening mechanism movable into and out of cooperative relation with a bag holder at said station, the 15 said bag opening mechanism including a spoon element mounted for reciprocating and rotating motion, the rotating motion being imparted to the spoon element upon entry into a bag in the holder, and means operative 20 on the said spoon element after it has partially entered and opened a bag for imparting thereto a quick angular motion to deliver a kick to the bag for opening the same to full capacity.

35 11. In a bag opening machine, a carrier provided with a bag holder movable through a plurality of operating stations including a bag opening station, a bag opening mechanism movable into and out of cooperative 25 relation with a bag holder at said station, the said bag opening mechanism including a spoon element mounted for reciprocating and rotating motion, the rotating motion being imparted to the spoon element upon entry 30 into a bag in the holder, and means operative on the said spoon element after it has partially entered and opened a bag for imparting thereto a quick angular motion to deliver a kick to the bag for opening the same to full capacity.

40 12. In a bag opening machine, a turntable provided with a plurality of spaced 45 holders arranged thereabout and each mov-

able through a plurality of operating stations including a bag opening station, a bag opening mechanism movable into and out of cooperative relation with a bag holder at 50 said station, the said bag opening mechanism including a spoon element mounted for reciprocating and rotating motion, the rotating motion being imparted to the spoon element upon entry into a bag in the holder, 55 and means operative on the said spoon element after it has partially entered and opened a bag for imparting thereto a quick angular motion to deliver a kick to the bag for opening the same to full capacity. 70

13. In a bag opening machine, a turntable provided with a plurality of spaced holders arranged thereabout, each holder being movable through a plurality of operating stations including a bag opening station, a bag 75 opening mechanism at the said bag opening station comprising a cross bar reciprocable in a vertical direction, an operating spoon rockably mounted on the said cross bar, a cam follower mounted on the said spoon and spaced from the rocking axis thereof, and a cam track in the path of movement of said cam follower.

14. In a bag opening machine, in combination, a bag holder and gripping means movable thereon for gripping the side edges of an opened bag in the holder for maintaining the same open, the said gripping means comprising spaced bell crank levers rockably mounted on the holder and means for rocking the said levers including a slide bar connected to the levers, and provisions for reciprocating the slide bar. 85

15. In a bag opening machine, in combination, a bag holder and gripping means movable thereon for gripping the side edges of an opened bag in the holder for maintaining the same open, the said gripping means comprising spaced bell crank levers rockably mounted on the holder and means for rocking the said levers including a slide bar connected to the levers, and provisions for reciprocating the slide bar, said provisions comprising a shaft transversely journalled in the holder, an arm connecting the shaft 90 with the slide bar, and reversely arranged actuating arms fixed to the shaft. 100

Signed at Middletown, in the county of Butler and State of Ohio, this 6th day of June, A. D. 1922.
